UNITED STATES PATENT OFFICE

104,034

DESIGN FOR A WALL BRACKET LAMP

Edward Kanter, Cleveland Heights, Ohio, assignor to Railley Corporation, a corporation of Ohio

Application October 21, 1936, Serial No. 65,403

Term of patent 7 years

To all whom it may concern:

Be it known that I, Edward Kanter, a citizen of the United States, residing at Cleveland Heights, in the county of Cuyahoga and State of Ohio, have invented a new, original, and ornamental Design for a Wall Bracket Lamp, of which the following is a specification, reference being had to the accompanying drawing, forming part thereof, wherein the single figure is a perspective view of a wall bracket lamp embodying my new design.

I claim:

The ornamental design for a wall bracket lamp substantially as shown.

EDWARD KANTER.
